UNITED STATES PATENT OFFICE.

HERMAN F. RICHTER, OF SEATTLE, WASHINGTON, ASSIGNOR OF ONE-TENTH TO
JOSEPH R. KETCHAM, OF SEATTLE, WASHINGTON.

TERMINAL CLAMP.

948,596.

Specification of Letters Patent.

Patented Feb. 8, 1910.

Application filed August 3, 1908. Serial No. 446,768.

To all whom it may concern:

Be it known that I, HERMAN F. RICHTER, a citizen of the United States of America, and a resident of the city of Seattle, in the 5 county of King and State of Washington, have invented certain new and useful Improvements in Terminal Clamps, of which the following is a specification.

My invention has particular reference to 10 a terminal connection and the primary object thereof is the provision of a simple and inexpensive electrical clamp for terminal connections.

Further objects and advantages will be 15 set forth as the description progresses and those features on which I desire protection defined in the appended claim.

With reference to the accompanying drawing, wherein like reference numerals 20 designate corresponding parts throughout: Figure 1 is a side view in partial section of an incandescent lamp socket illustrating an embodiment of my invention as the means for connecting the conducting wires thereto. 25 Fig. 2 is a transverse sectional view taken on line 2—2 of Fig. 1 and Figs. 3 and 4 are detail views illustrating the members of the socket which are equipped with my invention.

30 In Fig. 3 I have shown the features of the invention in connection with a base 1 constituting a detachable part of the screw-threaded member or terminal 2 of socket 5 while in Fig. 4 the invention is illustrated in 35 connection with the bearing plate 3 for the circuit controlling key 4 of said socket which is of an ordinary and well known type including a supporting block 6 in which plate 3 is mounted. While base 1 may be an integral part of member 2 I have shown the same 40 formed with an angular extension 2' which is provided with a screw threaded aperture 7 adapted for engagement with the clamping screw 8 of block 6 to secure the extension 45 in contact with the inwardly projecting flange 2'' of member 2, as indicated in Figs. 1 and 2.

50 Numeral 3' indicates the contact spring provided on plate 3 for connection, through the bridge piece 4' carried by the spindle of key 4, with the terminal 9 of the socket in the usual manner.

Referring now more particularly to the embodiment of my invention disclosed in Fig. 3 reference numerals 10 and 11 designate companion gripping members, the former as shown consisting of a forwardly projecting flange of base 1 and the latter comprising a circular disk supported eccentrically on said base for rotary movement 55 in either direction into clamping relation with member 10. While I preferably secure member 11 to its axle as 12 and journal the latter in base 1, as disclosed in Fig. 3, the axle may constitute a relatively fixed part 60 of the device and member 11 turn thereupon as will be readily understood. The gripping portions of jaws 10 and 11 are preferably serrated to insure a firm grip on the wire when the clamp is applied, and member 11 is preferably formed with a laterally projecting portion, as 13 which restricts the 70 space between the jaws at the open side of the clamp and tends to crowd the wire on jaw 10 against base 1. In the outer side 75 face of member 11 I have shown a groove 14 in which a screw drive may be engaged to turn the member. In connecting the socket with the drop wire 15, the latter is placed on base 1 between the clamping part and member 11 then turned upwardly toward member 10 until a firm grip is imposed on the wire. The relative arrangement of the members should be such that when the clamp is thus applied the point of greatest throw 80 of member 11 will fall below its axis, whereby downward pull or strain imposed on the socket will tend to tighten the clamp. 85

In Fig. 4 the gripping member 11' is rotatably mounted on a base 1' consisting of an 90 end portion of plate 3, while the companion member 10' is provided in the form of a serrated shoulder of said base, otherwise the construction and relative arrangement of these members is the same for gripping wire 95 16, as that of members 10 and 11 for gripping wire 15.

Having thus described my invention, what I claim as new, and desire to secure by Letters Patent of the United States of America, is:

An electrical connection comprising a base having an angularly disposed flange, and a disk supported eccentrically on said

base for rotary movement in either direction into clamping relation to the flange of said base, said disk having a projecting portion on its outer edge restricting the space between it and the flange of said base and tending to crowd the wire on said flange against said base.

Signed at Seattle, Washington this 24 day of July 1908.

HERMAN F. RICHTER.
